UNITED STATES PATENT OFFICE.

GEORGE F. CHAPMAN, OF MARLBORO, MASSACHUSETTS, ASSIGNOR OF ONE-HALF TO LEVI WALLACE, OF AYER, MASSACHUSETTS.

ADJUSTABLE HEADLIGHT FOR STREET-CARS, &c.

SPECIFICATION forming part of Letters Patent No. 712,260, dated October 28, 1902.

Application filed May 31, 1902. Serial No. 109,594. (No model.)

To all whom it may concern:

Be it known that I, GEORGE F. CHAPMAN, of Marlboro, in the county of Middlesex and State of Massachusetts, have invented certain new and useful Improvements in Adjustable Headlights for Street-Cars, &c., of which the following is a specification.

This invention relates to an automatically-adjustable headlight for street-cars and other vehicles; and it consists in the novel features of construction and relative arrangement of parts as set forth.

Figure 1 is a top plan view of a car-truck, the body of the car being removed and the vestibule being shown in dotted lines. Fig. 2 in side elevation shows a car equipped with my invention. Fig. 3 is a detail perspective view showing the lamp-supporting rod and its associated parts.

20 The same numerals of reference indicate the same parts in all the figures.

1 represents the railway, and 2 an ordinary car-truck.

3 represents the truck-beam.

25 4 represents an air-cylinder adapted to be charged from any source of power. This cylinder 4 may be suspended from the car-body in any desired way.

5 and 6 represent air-cylinders secured to the under side of the vestibule. In the cylinder 5 is arranged a piston-head 7, to which is connected a piston-rod 8, and in the cylinder 6 is arranged a piston-head 9, to which is connected a piston-rod 10.

35 11 represents a pipe connected at one end to the cylinder 5 and at its other end to the cylinder 4.

12 represents a pipe connecting the cylinder 6 with the cylinder 4.

40 13 represents a valve arranged in the pipe 11, the stem of which is connected with a lever 14.

15 represents a lug carried by the truck-beam 3 and adapted to engage the outer end 45 of the lever 14.

16 represents a spring connected at one end with the lever 14 and at its other end with the pipe 11. The spring 16 is arranged to normally keep the valve 13 closed. The pipe 50 12 is provided with a similar valve 20, lever 21, and spring 22. The lever 21 is arranged

to be engaged by a lug 23, carried by the truck-beam 3.

30 represents a bracket carried by the front end of the vestibule and provided with ears 55 31, in which is arranged a rod or lamp-post 32, formed with a flange 33, which rests on the top of the ear 31 and maintains the rod in position. The upper end of the rod is formed with a cross-piece 34. The lamp 35 is 60 formed with clips 36, arranged to engage with the cross-piece 34. These clips are held in place by the inturned ends 37 of the cross-piece 34. To the lower end of the rod are secured two arms 40 41.

65 42 represents a connecting-rod joined at one end to the free end of the arm 40 and at its other end to the front end of the piston-rod 10. The end of the arm 41 is connected in like manner by a rod 43 to the front end of 70 the piston-rod 8.

44 represents a spring connected at one end to the rod 42 and at its other end to a stationary support.

45 represents a spring connected at one end 75 to the rod 43 and at its other end to some stationary support. The spring 44 tends to counteract and steady the fluctuation of the piston-rod 10, while the spring 45 is designed for a similar function in connection with the 80 piston-rod 8.

The parts being constructed and arranged as described, and the light being positioned as shown, its rays will be deflected along the longitudinal axis of the car-body. If now 85 the wheels of the truck engage a curve whose center lies below the truck, as shown in Fig. 1, the latter will cause the upper wheels to travel in a circle greater than that followed by the lower wheels, the truck with respect 90 to the car-body turning on its swivel. Such action of the truck will cause the lug 15 to engage the lug 14 and open the valve in the pipe 11, thus operating the rod 8 to divert the rays of the lamp 35 to make them follow the 95 rail or roadway. If the curve was in the opposite direction, a similar result would be obtained by means of the lug 23 and the rod 10.

By this construction the rays of the light are automatically maintained on the rail or 100 roadway irrespective of the position of the longitudinal axis of the car-body.

I do not wish to be understood as limiting myself to the arrangement of pneumatic devices and connections shown, since any form of pneumatic connection for this purpose 5 might be employed without departing from the spirit of my invention.

I do not claim, broadly, in this application a lateral deflectable headlight and means for automatically turning the headlight toward 10 either side of its central position, since this invention is claimed by me in my application Serial No. 103,850.

While the light as described is represented as arranged to normally shine along the longitudinal axis of the car-body, I do not wish 15 to be limited to this arrangement, since the invention in its broad phase includes an adjustable light controlled by the truck or an equivalent device.

20 Having thus explained the nature of my invention and described a way of making and using the same, although without attempting

to set forth all of the forms in which it may be made or all of the modes of its use, what I claim, and desire to secure by Letters Patent, is—

1. A vehicle having a laterally-deflectable headlight, a truck, and pneumatic connections between said truck and light, whereby said light is deflected to shine upon the roadway, irrespective of the longitudinal axis of the vehicle. 30

2. A vehicle having a laterally-deflectable headlight, a truck, a pneumatic motor for controlling the position of the headlight, valve 35 mechanism for said motor, and valve-operating mechanism connected with the truck, substantially as described.

In testimony whereof I have affixed my signature in presence of two witnesses.

GEORGE F. CHAPMAN.
